UNITED STATES PATENT OFFICE.

FRANK R. BARNES, OF YOUNGSTOWN, OHIO.

CLIP.

Application filed July 23, 1925. Serial No. 45,689.

This invention relates to devices for holding cards such as ice cards or any card where it is desired that attention be drawn to the card held in the clip.

5 The object of the invention is to produce a device of this class which is simple in construction and which can be readily mounted upon a wall or post for the purpose stated.

10 More specifically, the object of the invention is to construct the device so that it can be economically manufactured. To this end, the device is of specific construction, which adapts it for being formed of a single 15 piece of wire or rod.

A further object of the invention is to provide a device that may be readily installed by using a single nail or screw.

With the foregoing and other objects in view which will appear as the description proceeds, the invention resides in the combination and arrangement of parts and in the details of construction hereinafter described and claimed, it being understood 25 that changes in the precise embodiment of the invention herein disclosed, can be made within the scope of what is claimed, without departing from the spirit of the invention.

30 The invention is illustrated in the accompanying drawing, wherein:—

Figure 1 is a front elevation of the device showing the same in proper position to attach to a wall or post or other suitable 35 support as desired.

Figure 2 is a side elevation of the device.

Figure 3 is a detailed view of Figure 1 showing a slight modification.

Figure 4 is a detailed view of Figure 1 40 showing a slight modification.

While the device adapts itself splendidly for the purpose of holding ice cards and the like, it is understood that this device may be utilized for many other purposes, where 45 it is desired to hold a card or any other material in a displayed position.

Referring more particularly to the drawing, 1 represents a horizontal base member provided with a central upturned and outwardly extending inverted U-shaped tension member 2. The horizontal base member 1 is provided with turns 3, wherein upwardly extending arms 4 are bent so as to come directly back of the horizontal base member 1 at points 5 which are equally spaced from the central upturned and out-

wardly extending inverted U-shaped tension member 2.

By referring to Figure 1, it will be seen that the upwardly extending arms 4 are turned outwardly at points 6 forming an inclined member 12, and then turned inwardly at points 7 in order to form an upper bar 8 parallel with the horizontal base member 1. The ends 9 are now secured together by means of welding, soldering or other suitable manner known to the art.

It will be seen by referring to Figures 1 and 2 that the ends 9 are turned upwardly and outwardly at points 10 thereby forming 70 a convenient operating handle or arm for the purpose of pulling the upper portion of the device which extends above the horizontal base member 1 for the purpose of inserting cards or other desired objects. In 75 installing the device a nail or screw is placed within the base of the opening 11 formed by the central upturned and outwardly extending inverted U-shaped tension member 2.

By referring to Figure 2, it will readily be seen by driving the nail or turning down the screw, this will cause the central upturned and outwardly extending converted U-shaped tension member 2 to be drawn in 85 against a wall or article to which the device is attached, thereby exerting an inward tension on the upwardly extending arms 4.

By referring to Figure 3, it will be seen that I have shown a modification of the device by eliminating the upper bar 8 by cutting the same at points 7.

By referring to Figure 4, it will be seen that if it is desired to secure the ends 9 without forming a handle or arm, the same may 95 be done by causing the extreme ends 13 to be placed, so as to be positioned end to end and then welded, at welding point 14.

Having thus described my invention, what I claim is:—

1. In a device of the class described, a 100 clip formed of a single piece of wire or rod having a horizontal base member, a central upturned and outwardly extending inverted U-shaped tension member, turns 105 formed so as to provide upwardly extending arms positioned directly back of the horizontal base member, inclined sections formed at the upper ends of the said upwardly extending arms, an upper bar 110 formed by bending the wire inwardly so as to be parallel with the horizontal base mem-

ber, upwardly and outwardly bent ends secured together by means of welding, substantially as described for the purpose set forth.

- 5 2. In a device of the class described, a clip formed of a single piece of wire or rod having a horizontal base member, a central upturned and outwardly extending inverted U-shaped tension member, turns 20 formed so as to provide upwardly extending arms positioned directly back of the horizontal base member, inclined sections formed at the upper ends of the said upwardly extending arms, substantially as described for the purpose set forth.
- 10 3. In a device of the class described, a clip formed of a single piece of wire or rod 25 having a horizontal base member, a central upturned and outwardly extending inverted U-shaped tension member, turns formed so as to provide upwardly extending arms positioned directly back of the horizontal base member, inclined sections formed at the upper ends of the said upwardly extending arms, substantially as described for the purpose set forth.
- 15 4. In a device of the class described, a clip formed of a single piece of wire or rod 30 having a horizontal base member, a central upturned and outwardly extending inverted U-shaped tension member, turns formed so as to provide upwardly extending arms positioned directly back of the horizontal base member, inclined sections formed at the upper ends of the said upwardly extending arms, substantially as described for the purpose set forth.

3. In a device of the class described, a clip formed of a single piece of wire or rod

having a horizontal base member, a central upturned and outwardly extending inverted U-shaped tension member, turns 20 formed so as to provide upwardly extending arms positioned directly back of the horizontal base member, inclined sections formed at the upper ends of the said upwardly extending arms, an upper bar 25 formed by bending the wire inwardly so as to be parallel with the horizontal base member, said bar with the ends welded end to end, substantially as described for the purpose set forth.

30 In testimony whereof I affix my signature.

FRANK R. BARNES.
